UNITED STATES PATENT OFFICE.

RALPH W. WALTER, OF MAZOMANIE, WISCONSIN.

COW-STANCHION.

1,350,480.

Specification of Letters Patent. Patented Aug. 24, 1920.

Application filed March 10, 1919. Serial No. 281,813.

To all whom it may concern:

Be it known that I, RALPH W. WALTER, a citizen of the United States, residing at Mazomanie, in the county of Dane and State 5 of Wisconsin, have invented certain new and useful Improvements in Cow-Stanchions, of which the following is a specification.

The purpose of this invention is to provide an improved type of cow stanchion 10 which is adapted to be operated simultaneously with others of the same type arranged in series in the usual manner, or which may be operated singly, if desired.

The principal object of the invention is to 15 provide a series of stanchions with means for opening any number of stanchions in the same row by a single operating mechanism located, preferably, at one end of the row. A further object is to provide means 20 for permitting the opening of any stanchion independently of the others. A further object is to provide means whereby one or more of the stanchions may be maintained in closed or locked position while the remaining stanchions in the same row are 25 open. Still another object is to provide means whereby any one or all of the cows in the row of stalls may be alined with the gutter at the rear of the stalls. A further 30 important object is to provide an automatic cow stop, or positioning means, which makes it necessary for the cow to put her head in the proper opening. Other objects relate to various features of construction and arrangement which are pointed out more fully 35 hereinafter.

The nature of the invention will be understood from the following specification taken in connection with the accompanying 40 drawings, in which one embodiment is illustrated.

In the drawings—

Figure 1 shows a top plan view of the top rails and operating mechanism;

Fig. 2 shows an elevation of a row of cow stalls to which the present invention is applied;

Fig. 3 is an enlarged elevation of the upper end of a stanchion and the mechanism 50 for controlling the opening and closing of the same;

Fig. 4 shows a detail cross-sectional view taken on the line 4—4 of Fig. 3; and

Fig. 5 shows a cross-sectional view taken 55 on the line 5—5 of Fig. 3.

Like numerals refer to the correspond-

ing parts in the several figures of the accompanying drawings, in which the invention is shown as comprising a series of stalls formed by the vertical posts 10, secured to 60 the floor 11 and attached at their upper ends to the horizontal supporting rails 12 by means of the bolts 13. In Figs. 1 and 2 of the drawings only the end stalls are illustrated, but any desired number may be 65 placed in the row between these end stalls, one of the posts 10 being mounted between each pair of stalls. Between the posts at the forward end of each stall is a stanchion 14 comprising the side bars 14^a, which are 70 pivoted at their lower ends to the horizontal supporting bar 14^b carried by a detachable supporting member 15 mounted on the floor 11. At their upper ends the arms 14^a are turned inwardly to meet at the point 17. 75 One of the arms of each stanchion is provided with an upwardly extending lug 18, which engages an aperture in the lower flange of a U-shaped bracket 19 secured between the horizontal supporting rails 12, 80 which are preferably of channel form, as shown in Figs. 4 and 5. The lug 18 is preferably secured in position by means of a pin 20, and can be withdrawn downwardly when desired. The other arm 14^a of each stanchion 85 is movable and carries at its upper end an upwardly extending arm 21^a and terminates above the top rails, as shown at 21^b. The opening and closing of the stanchions is effected by the movement of the 90 movable bar of each stanchion through the operation of the upwardly extending arm 21 in the manner hereinafter described.

A horizontally movable rod 25 is mounted to slide in bearings 26 carried by the rails 95 12. This rod is provided opposite a number of the stanchions with a clamp 27, which is pivoted at its lower end to a latch 28 having downwardly extending parallel flanges 28^a which enter the spaces between the rails. 100 Each latch is further provided with a forwardly extending tongue 28^b, which is provided with an aperture adapted to be engaged by the upwardly extending part 21^b of the arm 21 secured to the stanchion. 105 Upon movement of the operating rod 25 to the left, as viewed in Fig. 2, the latch 28 carries the arm 21 with it, and thereby separates the bars 14^a of the stanchions. A locking plate 30 is pivoted at 31 on a 110 flange 32, carried by the bearing member 26 adjacent each stanchion, and this locking

plate has an aperture or slot 30^a which permits the plate to be swung around into a position beneath the tongue 28^b of the adjacent latch 28. When in this position the plate 30 lifts the latch upwardly until the aperture becomes disengaged from the projection 21^b and the arm 21, thus permitting the latch to ride to the left, as viewed in Figs. 1 and 3, while the plate 30 retains the stanchion in closed position. This construction permits any selected stanchion in the row to be locked in closed position while the remaining stanchions are open. The rod 25 is reciprocated in a horizontal direction by a connecting rod 33, which is pivoted thereto and pivotally connected at 34 to an operating lever 35, of angular form, which is adapted to move about a pivot 36 secured between the rails 12. The lever 35 may be locked in its normal closed position by a chain latch 37.

In order to permit certain of the cows in the row to be spaced rearwardly from the line of posts 10, so that all of the cows will be alined with the gutter at the rear of the stalls, some of the stalls 14 are spaced rearwardly by means of brackets 40, having the form illustrated particularly in Fig. 1. Each bracket is detachably secured to the rails 12 by means of bolts 41 and spacing collars 42, and the bracket comprises parallel flanges 40^a which are located outwardly from and parallel to the rails. The stanchion beneath the brackets 40 has its support 15 mounted rearwardly from the line of posts 10, and the bracket 19 at the upper end thereof is secured to the bracket 40, instead of being attached directly to the rails. The movable arm 21, carried by the stanchion, extends upwardly between the flanges 40^a and is adapted to be engaged by a latch 28, of the form previously described, which is pivoted on the V-shaped supporting member 43 carried by the adjacent clamp 27 and by another clamp 44 attached to the operating rod 25. Locking plates 30 may be mounted on any of the brackets 40, in the manner previously described, so that they may be swung around under the latches 28 for the purpose of holding the stanchion closed when the others are opened. By means of this construction any stanchion which is spaced rearwardly from the row of posts 10 may be operated simultaneously with the other stanchions which are located in the same vertical plane with the posts, or it may be held closed while the others are opened.

For the purpose of causing the cows to place their heads between the bars of the stanchions, I have provided automatic means for closing the spaces between the posts and the bars of the stanchions at the same time that the latter are opened. At the end of the row of stalls adjacent the op-

erating lever 35 I provide an upwardly extending bar 45, which is pivoted at its lower end to a link 46 having a pivotal connection with the lower part of the adjacent post 10. The upper end of the bar 45 is pivoted to 70 the lever 35, so that when the lever is swung upwardly and inwardly the bar 45 is carried inwardly to close the space between the post 10 and the adjacent fixed arm 14^a of the stanchion. The spaces between the intermediate posts of the row and the adjacent bars of the stanchions are closed, simultaneously with the opening of the stanchions, by means of levers 47 and 48, which are pivoted at their intermediate points on 75 the posts and carry upwardly extending bars. One of these bars 49 is pivoted to the end of the lever 47, and the lower end thereof passes loosely through a ring 48^a carried by the extremity of the lower level 80 48. Another vertically extending rod 50 is pivoted to the ends of the levers 47 and 48, opposite the rod 49, and extends upwardly between the rails 12, being pivotally connected at its upper end to a link 51. This 85 link is pivotally connected to a clamp 52 secured to the actuating rod 55, so that upon movement of said rod to the left, as viewed in Fig. 2, the rod 50 moves downwardly and outwardly from the post 10, thereby causing an upward and outward movement of the rod 49 on the opposite side of the post. These rods thus occupy the 90 spaces between the posts and the adjacent stanchions, so that the heads of the cows 100 are directed toward the openings through the stanchions. At the end of the row of stanchions opposite the operating lever 35 a fixed rod 53 is mounted in inclined position, being connected to the floor at 54 and to the 105 upright post 10 at the point 55, thus closing the spaces between the end post and the adjacent stanchion 14.

By means of the foregoing construction it will be apparent that any desired stanchion 110 may be locked in closed position while all of the others are simultaneously opened, or any stanchion, or group of stanchions, may be opened while all the others are locked in closed position. At the same time that the 115 stanchions are opened the movable bars 45, 49, and 50 are moved into the spaces between the posts and the stanchions, so that the cows are directed into the openings between the stanchion bars. The brackets 40 120 may be of any desired size in order to place any stanchion at any desired distance from the row of posts 10 to effect the proper alinement of the cows in the row.

Although I have shown and described a 125 particular embodiment of the invention for purposes of illustration, it will be understood that it may be constructed in various different forms without departing from the scope of the appended claims.

I claim:—

1. In combination, a series of stanchions, a longitudinal supporting rail above said stanchions, a longitudinally slideable rod carried by said rail, latch members carried by said rod and engaging said stanchions to operate the same, and individual locking means carried by said rail adjacent each of said stanchions for locking said stanchions 10 in closed position and simultaneously rendering inoperative the latch member adjacent thereto.

2. In combination, a series of stanchions a longitudinal supporting rail above said 15 stanchions, a longitudinally slideable rod carried by said rail, a projecting lug carried by each of said stanchions, latch members pivoted on said rod and having parts engaging said lugs to open and close said 20 stanchions upon longitudinal movement of said rod, and locking members each mounted on said rail adjacent one of said stanchions and adapted to be operated independently to secure said stanchion in closed 25 position and simultaneously move the adjacent latch member out of engagement with the adjacent lug.

3. In combination, a series of stanchions, a supporting rail extending adjacent to said 30 stanchions, a longitudinally slideable rod carried by said rail, lugs projecting from each of said stanchions adjacent said rail, latch members pivoted on said rod and provided with apertures to be engaged by said lugs, 35 and supplementary locking means movable under said latch members to hold any of them out of engagement with said lugs during the movement of said rod.

4. In combination, a series of stanchions, 40 a supporting rail extending adjacent to said stanchions, a longitudinally slideable rod carried by said rail, lugs projecting from each of said stanchions adjacent said rail, latch members pivoted on said rod and provided 45 with apertures to be engaged by said lugs, and a locking plate adapted to be swung into a position beneath one of said latch members to engage the adjacent lug and thereby hold the adjacent stanchion in closed position 50 while permitting free movement of said latch member over said lug.

5. In combination, a pair of upwardly extending posts, a longitudinal rail carried by said posts, a longitudinally slideable rod 55 mounted above said rail, a stanchion comprising side arms mounted between said posts, a bracket secured to said rail and connected to one of said arms, an operating member extending upwardly from the other 60 of said arms adjacent said rail, a latch member pivoted on said rod and extending downwardly therefrom longitudinally of said rail, said latch member having an aperture to be engaged by said operating member, and a 65 locking plate adapted to be swung into a po-

sition beneath said latch member, said locking plate having a notch to engage said operating member and being adapted to hold said latch member out of engagement with said operating member.

6. In combination, a pair of upwardly extending posts, a longitudinal rail carried by said posts, a longitudinally slideable rod mounted above said rail, a stanchion comprising side arms mounted between said 70 posts, a bracket secured to said rail and connected to one of said arms, an operating member extending upwardly from the other of said arms adjacent said rail, a latch member pivoted on said rod and extending downwardly therefrom longitudinally of said rail, said latch member having an aperture to be engaged by said operating member, a locking plate adapted to be swung into a position beneath said latch member, said 75 locking plate having a notch to engage said operating member and being adapted to hold said latch member out of engagement with said operating member, said latch member being adapted to ride freely over said operating member when said locking plate is in operation, and a guiding flange secured to said latch member and extending downwardly therefrom adjacent said rail.

7. In combination, a series of vertical 95 posts, a supporting rail carried by said posts, a series of stanchions each mounted between two of said posts, a bracket secured to one side of said rail and extending laterally therefrom between two of said posts, said 100 bracket comprising parallel flanges extending parallel to said rail, each stanchion comprising relatively movable side arms, means carried by said rails and by said bracket for supporting the upper ends of one side arm 105 of each stanchion, operating members carried by the other side arms of said stanchions, said operating members extending upwardly adjacent said rail from some of said stanchions and between the parallel 110 flanges of said bracket from the other of said stanchions, an operating rod supported by said rail and latch members pivoted on said rod and resting on said rail and said bracket for engaging the operating members of said 115 stanchions.

8. In combination, a series of upwardly extending posts, a series of stanchions each mounted between a pair of posts, an upper lever and a lower lever pivoted at intermediate points on an intermediate post, a bar pivoted to one end of said upper lever and depending therefrom, one end of said lower lever having a slot loosely engaged by said bar, a second bar pivotally connected to the 120 other ends of both of said levers and projecting upwardly beyond said upper lever, a rod slidably mounted above said stanchions and movable longitudinally of the series of stanchions for opening and closing them, and 125 130

a link pivotally connected to said rod and to the upper end of said second named bar for moving both of said bars toward and away from said stanchions simultaneously with the opening and closing of said stanchions.

9. In combination, a longitudinal supporting rail, a series of stanchions each having a movable side bar, an arm attached to each of said movable side bars and extending upwardly therefrom, a bracket secured to the side of said rail and extending outwardly therefrom adjacent one of said stanchions, means carried by said rail and by said bracket for supporting the upper parts of said stanchions, a longitudinally slidable rod mounted above said rail, a supporting member attached to said rod and extending outwardly therefrom adjacent said bracket, and latch members attached to said supporting member and to said rod for engaging said upwardly extending arms of said stanchions.

10. In combination, a series of upwardly extending posts, a pair of rails secured to

opposite sides of the upper ends of said posts, a series of stanchions each mounted between a pair of said posts, each stanchion comprising a pair of side arms, means for supporting the lower ends of said side arms, a detachable spacing member secured to the side of one of said rails and extending outwardly therefrom, brackets secured to said spacing member and to said rails for supporting the upper end of one arm of each of said stanchions, operating members secured to the other arms of each of said stanchions and extending upwardly therefrom, an operating rod slidably mounted above said rails and extending longitudinally thereof, a supporting member secured to said rod and extending outwardly therefrom above said spacing member, and latch members pivoted on said supporting member and on said rod for engaging said upwardly extending operating arms.

In testimony whereof, I have subscribed my name.

RALPH W. WALTER.
